UNITED STATES PATENT OFFICE.

CARL A. MACKAY, OF BOSTON, MASSACHUSETTS.

DEVICE FOR REMOVING CROSS-HEADS.

SPECIFICATION forming part of Letters Patent No. 311,769, dated February 3, 1885.

Application filed October 8, 1884. (No model.)

To all whom it may concern:

Be it known that I, CARL A. MACKAY, of Boston, in the county of Suffolk, State of Massachusetts, have invented a certain new and useful Improvement in Devices for Removing Cross-Heads, of which the following is a description sufficiently full, clear, and exact to enable any person skilled in the art or science to which said invention appertains to make and use the same, reference being had to the accompanying drawings, forming a part of this specification, in which—

Figure 1 is a vertical longitudinal section of the piston-rod and cross-head and a side elevation of the wedge and keys, the wedge being represented as but partially inserted and the cross-head in position for use on the rod; Fig. 2, a like view representing the wedge fully inserted and the cross-head started from its seat or loosened on the rod, and Fig. 3 an isometrical perspective view of the wedge and keys detached.

Like letters of reference indicate corresponding parts in the different figures of the drawings.

My invention relates to means for removing the cross-heads of piston-rods, &c.; and it consists in a novel construction and arrangement of the parts, as hereinafter more fully set forth and claimed, by which a more effective device of this character is produced than is now in ordinary use.

The nature and operation of the improvement will be readily understood by all conversant with such matters from the following explanation, its extreme simplicity rendering an elaborate description unnecessary.

In the drawings, A represents the rod; B, the cross-head; C, the outer key; D, the inner key, and E the wedge. The outer key, C, is provided with two laterally-projecting flanges or shoulders, x x, and with a centrally-arranged elongated notch, d, in its outer edge or side. The inner key, D, is provided with two elongated notches, f g, and a centrally-arranged laterally-projecting flange, i, on its outer edge or side. The flange i is adapted to press against the main portion of the rod A, and the notch d to receive the end portion of said rod when the key C is forced outwardly by the wedge E, as hereinafter described.

In the use of my improvement the usual key which holds the cross-head onto the rod is removed and the keys C D and wedge E inserted in the key-hole, as shown in Fig. 1, the 55 flange i resting against the body or main portion t of the rod A, and the notch d standing astride the end portion, l, of said rod.

After the keys and wedge have been adjusted as shown in Fig. 1, the wedge is driven 6c in between the keys, causing the flange i to press inwardly against the rod at t, and the flanges x to press outwardly against the cross-head at z, and thereby force the cross-head from the rod, in a manner which will be readily 65 obvious without a more explicit description.

The keys are respectively provided with heads r, to prevent them from entering the key-hole in the cross-head and rod too far as the wedge E is driven in.

Having thus explained my invention, what I claim is—

1. In a device for removing the cross-head from a piston-rod, the combination of the following instrumentalities, to wit: two keys and 7c a wedge adapted to fit the ordinary key-hole in the cross-head and rod, one of said two keys being provided with a flange adapted to abut against the end of the main portion of the rod within the key-hole, and two notches 8c or depressions adapted to receive a portion of the inner end of the cross-head as it moves from the rod, and the other provided with two flanges adapted to abut against a portion of the outer end of the cross-head within the 8: key-hole, and a notch or depression adapted to receive the end portion of the rod within the key-hole as the cross head moves from the rod, substantially as described.

2. The keys C D and wedge E, in combination with the rod A and cross-head B, substantially as set forth.

3. In a device for removing the cross-head from a piston-rod, the key C, provided with the flanges x and notch d, the key D, provided 9c with the notches f g and flange i, and the wedge E, substantially as described.

CARL A. MACKAY.
